FOREIGN PATENT DOCUMENTS

WO DM/064351 * 9/2003

Primary Examiner—Michael J. Carone*(74) Attorney, Agent, or Firm*—Nelson Mullins Riley & Scarborough, LLP**CLAIM**

The ornamental design for a container, substantially as shown and described.

DESCRIPTION

FIG. 1 is a perspective view of a container embodying the design of the present invention;

FIG. 2 is a front elevational view of the container illustrated in FIG. 1, the rear view and side views being a mirror image of the front view;

FIG. 3 is a top view of the container illustrated in FIG. 1; FIG. 4 is a bottom view of the container illustrated in FIG. 1; and,

FIG. 5 is a bottom perspective view of the container illustrated in FIG. 1.

1 Claim, 3 Drawing Sheets

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.
